(57) **CLAIM**

The Ornamental design for a sheet of disposable drug formulation pouches, as shown and described.

DESCRIPTION

FIG. 1 is a 3-D isometric angled view of a sheet of disposable drug formulation pouches, showing the new design;

FIG. 2 is a top down view thereof;

FIG. 3 is a bottom up view thereof;

FIG. 4 is a side view thereof; and,

FIG. 5 is an exploded view of separated individual disposable drug formulation pouches making up the sheet of disposable drug formulation pouches as shown in FIG. 2.
